UNITED STATES PATENT OFFICE.

JULIUS C. GOODWIN, OF KALAMAZOO, MICHIGAN.

OAR-LOCK.

SPECIFICATION forming part of Letters Patent No. 235,355, dated December 14, 1880.

Application filed April 29, 1880. (Model.)

To all whom it may concern:

Be it known that I, JULIUS C. GOODWIN, of Kalamazoo, in the county of Kalamazoo and State of Michigan, have invented a new and useful Improvement in Oar-Locks, of which the following is a specification.

My invention relates to improvements in oar-locks in which two flanged rings are so arranged that they support between their flanges (and form a bearing for) a third or thole-pin ring, within the radius of which the two flanged rings before mentioned revolve, and in which the thole-pin ring has two projections, between which a thole-pin having a cross-head is inserted and secured by means of a bolt, thereby forming a hinge or joint.

The objects of my invention are, first, to provide a system whereby an oar can be easily held in horizontal position; second, to relieve the oar of unnecessary friction by means of a joint or hinge between the oar and the point of its conjunction with the boat; third, to provide, in conjunction with the above, a system which is susceptible of imparting an easy rotary motion to the oar to which it is attached, or, in nautical parlance, to enable the operator to "feather" the oar with greater ease and facility. I attain these objects by means of the appliances in the accompanying drawings.

In the accompanying drawings, in which similar letters of reference indicate like parts, Figure 1 is a perspective of a device embody-

ing my invention. Fig. 2 are the detached parts of the same.

Within the projections D of the thole-pin 35 ring C is inserted the cross-head A of the thole-pin B and secured by the bolt E. The two flanged rings F F are applied as follows: No. 1 F is secured to the oar G by means of screws inserted in the hole H. The thole-pin 40 ring C is then slipped onto the ring thus secured so far as the flange will admit, and is followed by the flanged ring No. 2 F, in the reverse order of No. 1 F, and is fastened to its place, as shown in the perspective, by means 45 of screws inserted through the hole i in the thole-ring C, which corresponds in position to the holes H in the flanged rings F.

The oar G and the bracket j constitute no part of my invention; but

What I do claim, and desire to secure by Letters Patent, is—

In an oar-lock, a thole-pin provided with a thole-pin ring hinged thereto, in combination with two flanged rings adapted to be inserted from opposite sides within said thole-pin ring, to form a bearing therefor, and secured to the oar by screws or other suitable devices, substantially as and for the purpose set forth.

JULIUS C. GOODWIN.
